(57) **CLAIM**

The ornamental design for a battery, as shown and described.

DESCRIPTION

FIG. 1 is a top view of a first exemplary embodiment of a battery showing my new design;

FIG. 2 is a left side view of the battery of FIG. 1;

FIG. 3 is a front view of the battery of FIG. 1; and,

FIG. 4 is a bottom view of the battery of FIG. 1.

The broken lines are provided for illustrative purposes only, and form no part of the claimed design. In addition, the portions of the battery that are not shown in the drawing do not form any part of the claimed design.
